UNITED STATES PATENT OFFICE.

WILLIAM KIMMEL, OF MILTON, INDIANA.

GANG-PLOW.

SPECIFICATION forming part of Letters Patent No. 341,250, dated May 4, 1886.

Application filed July 7, 1885. Serial No. 170,893. (No model.)

To all whom it may concern:

Be it known that I, WILLIAM KIMMEL, of Milton, in the county of Wayne and State of Indiana, have invented certain new and useful 5 Improvements in Gang-Plows; and I do hereby declare the following to be a full, clear, and exact description of the same, reference being had to the accompanying drawings, forming a part of this specification, and to the figures and 10 letters of reference marked thereon.

My invention relates to improvements in gang plows, and especially to that class in which a traction-engine or like propelling-motor is employed to draw the plows across the 15 field; and it consists in certain improved details of construction, which will be hereinafter fully described, and pointed out particularly in the claims at the end of the specification.

In the accompanying drawings, Figure 1 20 represents a top plan view of my invention; Fig. 2, a longitudinal section of the same, taken on the line $x-x$ of Fig. 1. Fig. 3 is a cross-sectional view taken on the line $y-y$ of Fig. 1; Fig. 4, an end view, with the plow-beams broken off, as shown by the section-lines; Fig. 25 5, a sectional view taken on the line $z-z$ of Fig. 1, looking toward the rear; Fig. 6, a detached view of the coupling by which the plow-beam is connected to the adjustable frame. Fig. 7 is a view of a modification of the means 30 for adjusting the depth at which the plows run, and Fig. 8 a similar view of a modification of the means for adjusting the plow on its horizontal axis.

Similar letters of reference in the several 35 figures indicate the same parts.

The letters A A each indicate a metal frame, such as each plow-beam is connected to. These frames may be two, three, or more in number; 40 but however many are employed, they are made of varying lengths, so as to bring their connected plows in diagonal ranks, as usual. Each of these metal frames consists of two longitudinal bars, $a a$, connected at their rear end by a cross-piece, a' , and at intermediate points 45 between their ends by reversely screw-threaded cross-bars or bolts a^2 , which pass through perforations in said bars, and are held by means of locking-nuts $a^3 a^4$, applied on the inside and outside of the said longitudinal bars, respectively. By changing the

position of these locking-nuts the frames may be made wider or narrower, and rigidly held in their adjusted positions. The forward or wider end of each frame is perforated, as shown 55 in Fig. 2, for the accommodation of a cross-shaft or through-rod, B, common to all the frames. The connection of the frames to this through-rod is such as to permit of the independent swinging motion of each of them upon 60 it as a pivot.

I may construct the through-rod of a solid piece of metal or of metal tubing—such as gas-piping; but I do not desire to limit myself to the use of either of these constructions exclusively.

Mounted upon the through-rod, between the frames A, are arranged two adjustable collars or stops, C, that are adapted to be moved longitudinally upon the through-rod, and locked 70 where desired thereon by means of set-screws c or other equivalent means. By means of these adjustable collars the frames are kept in their proper relative positions, and are enabled to be adjusted nearer to or farther from 75 each other, and thereby increase or diminish the distance between the plows connected to them. Straps or other suitable couplings—such as D—are applied to the through-rod B, and serve to connect the frames to the traction- 80 engine or other power arrangement.

E represent the forward ends of the plow-beams, (the plows, of ordinary construction, not being shown.) Each of these plow-beams is connected by means of a break-pin, e , to the 85 head of what may be termed a "coupling," F, whose shank f passes through the cross-piece or end plate, a' , of the frame A, and carries on its squared end a toothed wheel or segment, G, with the teeth of which meshes a short 90 worm-shaft, H. By the operation of this worm-shaft the coupling is rotated to the right or to the left upon its horizontal axis, thereby causing the plow-beam and the connected plow to be canted to the right or to the left correspondingly, and, in order that no unusual strain will be exerted upon the break-pin by reason of thus canting the plow, the end of the plow-beam is widened vertically, and the coupling is provided with an elongated recess to receive 100 it, from which it results that upon the turning of the coupling the plow-beam will be turned,

not by reason of the break-pin, but because of the impingement of its said widened end upon the walls of the elongated recess or slot in the coupling-head, as will be readily understood.

5 When in operation either of the plows meets with an immovable obstruction, the break-pin will be parted, thus guarding against breakage of the plow.

In lieu of the toothed wheel and worm-shaft to for imparting rotary motion to the coupling, I may employ simply a hand-lever, I, having ratchet-teeth on its opposite sides, and adapted to engage with pawls K K, pivoted upon the frame A. The lower end of this hand-lever is 10 passed through an opening in the shank of the coupling, as shown in Fig. 8. By moving the hand-lever to right or left until the desired point of adjustment of the plow is reached, then engaging with it the pawls, it will be securely locked in position.

For the purpose of causing the plows to run deeper or shallower, as desired, I provide each of the independent frames A with an adjustable gage-wheel, L, mounted between arms l, 25 that are pivoted at their upper ends to said frame. A screw-shaft, m, mounted in an oscillating block, n, so as to turn freely therein, co-operates with a corresponding screw-nut, having its bearings in said arms l, to effect the 30 raising or lowering of the said gage-wheel, according as the said screw-shaft is rotated in one or the other direction. This provision renders it practicable to at any moment change the depth at which the plows run without the necessity 35 of taking any portion of the machine apart.

As a substitute for the last described arrangement, I may employ that shown in Fig. 7, consisting of the pivoted lever O, bearing at its lower end the gage-wheel, and at its 40 upper end a sliding pawl, that is adapted to engage with one or the other of the teeth of a

fixed segment, P. I do not, however, regard this as desirable an arrangement as the first-described one.

Having thus described my invention, what 45 I claim as new, and desire to secure by Letters Patent, is—

1. In a gang-plow, the independent adjustable frames consisting of the longitudinal bars, the end piece, and the reversely screw-threaded 50 cross-bars provided with the nuts for clamping and holding the longitudinal bars in the desired position of adjustment, substantially as described.

2. In a gang-plow, the combination of the 55 through-rod, the independent adjustable frame connected thereto, having the coupling at its outer end, consisting of the head to which the plow-beam is attached and the shank provided with means for rotating and locking it, sub- 60 substantially as described.

3. In a gang-plow, the combination, with the independent frame of the plow-beam, the rotatable coupling between the beam and said frame, the toothed wheel or segment on the 65 shank of said coupling, and the worm-shaft, substantially as described.

4. In a gang-plow, the combination, with the independent adjustable frames and their adjustable gage-wheels, of the plow-beams 70 coupled to said frames, and means, substantially as described, for rotating and locking said couplings, as set forth.

5. In a gang-plow, the combination, with the through-bar, of the independent frames of 75 different lengths hinged to said through-bar and the plows connected to said frames by couplings, substantially as described.

WILLIAM KIMMEL.
